(57) **CLAIM**

The ornamental design for a dispenser, as shown and described.

DESCRIPTION

FIG. 1 is an isometric view of a front, top, and left side of an ornamental design for a dispenser;

FIG. 2 is a front elevational view of the dispenser of FIG. 1; FIG. 3 is a rear elevational view of the dispenser of FIG. 1; FIG. 4 is a left side elevational view of the dispenser of FIG. 1;

FIG. 5 is a right side elevational view of the dispenser of FIG. 1;

FIG. 6 is a top plan view of the dispenser of FIG. 1;

FIG. 7 is a bottom plan view of the dispenser of FIG. 1;

FIG. 8 is an isometric view of a front, top, and left side of an ornamental design for another embodiment of a dispenser;

FIG. 9 is a front elevational view of the dispenser of FIG. 8;

FIG. 10 is a rear elevational view of the dispenser of FIG. 8; FIG. 11 is a left side elevational view of the dispenser of FIG. 8;

FIG. 12 is a right side elevational view of the dispenser of FIG. 8;

FIG. 13 is a top plan view of the dispenser of FIG. 8; and, FIG. 14 is a bottom plan view of the dispenser of FIG. 8.

It is understood that the bounds of the claimed design are represented by shade lines to the end of the solid lines of the dispenser at the left and right sides, and top and bottom ends of the dispenser depicted in FIGS. 1-7, and to the end of the solid lines of the dispenser at the left and right sides, top and bottom ends, and corners of a front side of the dispenser depicted in the embodiment of FIGS. 8-14. Some of the dashed lines in FIGS. 1-14 represent apertures or recesses, which are not positively claimed in the representative embodiments. All other broken lines are for the purpose of depicting environmental structure and form no part of the claimed design.
